(57) **CLAIM**

What is claimed is the ornamental design for a stand mixer head, as shown and described.

DESCRIPTION

FIG. 1 is a perspective view of a stand mixer head;

FIG. 2 is a first side-view of the stand mixer head;

FIG. 3 is a second side-view of the stand mixer head;

FIG. 4 is a front view of the stand mixer head;

FIG. 5 is a rear view of the stand mixer head;

FIG. 6 is a top view of the stand mixer head; and,

FIG. 7 is a bottom view of the stand mixer head.

The dotted lines are provided for illustrative purposes only and form no part of the design claimed.
